(57) **CLAIM**

The ornamental design for a solar light, as shown and described.

DESCRIPTION

FIG. 1 is a three-demensional view of a solar light in accordance with my invention;

FIG. 2 is a front view of the solar light shown in FIG. 1; FIG. 3 is a side view of the solar light shown in FIG. 1; FIG. 4 is a top view of the solar light shown in FIG. 1; and, FIG. 5 is a bottom view of the solar solar light shown in FIG. 1.

The broken lines shown on the drawings are for illustrative purposes only and form no part of the claimed design.

1 Claim, 2 Drawing Sheets Fig. 5
